ANVIL-PEDAL.

1,131,320.

Specification of Letters Patent.

Patented Mar. 9, 1915.

Application filed May 27, 1914. Serial No. 841,843.

To all whom it may concern:

Be it known that we, HERBERT R. BLISS and LEONARD JOHNSTON, citizens of the United States, residing at Detroit, county of Wayne, State of Michigan, have invented a certain new and useful Improvement in Anvil-Pedals, and declare the following to be a full, clear, and exact description of the same, such as will enable others skilled in the art to which it pertains to make and use the same, reference being had to the accompanying drawings, which form a part of this specification.

This invention relates to a combined pedal and latch for swinging out of operative position a swinging anvil support or spindle.

In the drawings,—Figure 1, is a side elevation of the anvil and anvil spindle showing the base which supports the anvil in section, the section being taken on the line A—A of Fig. 3. Fig. 2, is a vertical section taken on the line B—B of Fig. 1. Fig. 3, is a top or plan view of the pedal, the base that supports the anvil spindle and the locking device. Fig. 4, is a vertical section through the spindle bearing. Fig. 5, is a perspective of the combined pedal and latch release.

a designates an anvil which is intended to be used primarily to support a fiber shipping case which is undergoing wire stitching or fastening by wire fasteners.

b represents the spindle which supports the anvil. This spindle fits into a sleeve or bearing c which is provided with a transversely disposed tubular end d through which engages the pin e that journals the bearing to the brackets f that depend from the base g. The base g is the conventional form of casting used as the base of a machine and is not solid but hollow inside to accommodate some of the operating parts of the machine. Surmounted on this base and about the bearing c is a removable housing h. This housing h contains the spring j which normally presses the latch k into the recess in which the spindle bearing c swings.

When the spindle bearing has been thrown back against the adjusting screw l, the shoulder or hook m on the end of the latch k engages with the forward face of the bearing c and holds the anvil spindle b firmly in place. It is necessary that this anvil spindle be held firmly in a given position so as to

insure the anvil being in correct position under the operating parts of the metal fastener driving machine. By turning the adjusting screw l the exact position of the anvil with respect to the operating parts of the machine can be fixed. The latch is initially set in correct position so that it will not require subsequent adjustment. If for any reason it should get slightly loose the adjusting screw l may be turned slightly to insure the tight gripping of the hook on the latch when the bearing has swung back into place.

The forward face of the bearing c has a slot T-shaped in cross-section. This slot is designated n and is adapted to receive the T bar end o of the pedal p. This T bar end can be dropped into the T slot from the top and will rest against the pin q at the bottom. This affords a removable connection between the spindle bearing c and the pedal so that the pedal together with the latch release may be easily disengaged so as to allow the spindle b to be swung clear down after the spring r has been taken off of the hook s. This is desirable because it may be desired to use the operating head of the wire stitching machine for other purposes and the anvil shown in the drawings will not be required.

Pivoted to the pedal p is a latch release in the form of a slightly bent bar t which has an up-turned and obliquely cut end u. The oblique edge of this end engages with the hook on the latch, as shown in Fig. 3, the latch being over the oblique edge so as to tip the free end of the latch release slightly above the free end of the pedal p as shown in Fig. 5. Consequently when one steps on the free ends of the two pedals, the foot first depresses the pedal t to a position of parallelism with the pedal p. This forces the obliquely cut end u of the pedal t upward, causing the latch to go to the side as shown in the dotted lines of Fig. 3. This takes the latch out of the path of the bars c. Consequently the pedal p now causes the spindle b to drop forward where the position of the case upon the anvil may be changed or the case may be removed and another case inserted over the anvil.

The anvil may be thrust back to its operating position by hand or else the spring r may be used to pull it back automatically. Immediately that it has passed the hooked

end of the latch the spring causes the hook or shoulder *m* of the latch to again engage the forward side of the bar *c* and hold the anvil spindle firmly in position.

5 From the above description it will be seen that by a single operation of the foot both the latch is released and the anvil tipped toward the operator. Also by reason of the arrangement of the pedal and the latch release together they may easily be detached from the pedal so as to allow the pedal to fall completely forward and out of the way when the machine is desired for other purposes.

10

15 What we claim is:

1. The combination of a swinging anvil spindle, a base for pivoting the same, a stop to limit the swing of the anvil spindle in one direction, a spring-actuated latch for engaging the anvil spindle on the opposite side of the stop to hold it in position, and a combined pedal and latch release adapted to retract the latch from engagement with the spindle and pull the anvil spindle toward the operator.

2. The com-

2. The combination of an anvil spindle, a base to which the anvil spindle is pivoted, a stop to limit the swing of the anvil spindle in one direction, a spring-actuated latch for engaging the anvil spindle on the side opposite the stop to hold the spindle in a given position, a pedal attached to the anvil spindle for swinging the anvil spindle forward

when the latch is released, and a latch release comprising a bar pivoted to the pedal and having an obliquely cut end which engages with the latch, the said obliquely cut end being ordinarily on the latch so as to force the free end of the latch release above the free end of the pedal. 35

3. The combination of an anvil spindle, a base to which the same is pivoted, a stop to limit the swing of the anvil in one direction, a spring-actuated latch for engaging the side of the anvil spindle opposite the stop, a portion of the anvil spindle being provided with a vertical slot T-shaped in cross-section and having a stop at the lower end of the slot, a pedal provided with a T-bar end for fitting into the T-shaped slot, and a latch release pivoted to the pedal and provided with an obliquely cut up-turned end adapted to engage with and to be normally pressed by the latch so that the free end of the latch release is held above the free end of the pedal. 40

In testimony whereof, we sign this specification in the presence of two witnesses.
